UNITED STATES PATENT OFFICE

2,137,772

AUTOGRAPHIC REGISTER

Louis Jensen, Chicago, Ill., assignor to United Autographic Register Co., Chicago, Ill., a corporation of Illinois

Application April 24, 1936, Serial No. 76,241

7 Claims. (Cl. 282—16)

This invention relates to autographic registers and more particularly to an improved feeding, aligning, and re-folding mechanism for continuous-form stationery used therein.

5 The primary object of the invention is to provide aligning means, such as register pins for engaging perforations in each form length of the stationery to register the same over the platen and to provide mechanism for disengaging the 10 stationery from each alternate form length of the stationery record strip which is projected into a record compartment. Thus it will be understood that the pins will allow one form length to be projected to the rear of the compartment and will 15 carry the next form downwardly so as to insure its proper re-folding beneath the feed mechanism.

Heretofore re-folding of this nature has been accomplished by providing a register perforation in alternate form lengths and providing a yieldingly urged pin to engage said perforation when it is presented to the feed mechanism. In the present invention no special perforations are provided.

The invention is illustrated in the preferred 25 embodiment in the accompanying drawings, in which—

Fig. 1 is a broken longitudinal sectional view of an autographic register embodying the invention taken as indicated at line 1—1 of Fig. 5; 30 Fig. 2, a fragmentary longitudinal sectional view taken as indicated at line 2—2 of Fig. 5, and showing the differential cam mechanism for retracting the pins; Fig. 3, a broken longitudinal sectional view similar to Fig. 1 showing the pins being retracted at the beginning of a revolution to permit the record strip to be projected to the rear end of the compartment; Fig. 4, a view similar to Fig. 3 showing the mechanism after making about one and one-fourth turns from the position shown 40 in Fig. 3 with the pins carrying the form to be re-folded toward the front of the machine; and Fig. 5, a transverse sectional view taken as indicated at line 5—5 of Fig. 1.

In the embodiment illustrated, A designates an 45 autographic register having a supply compartment A¹ and a record compartment A²; B, feed mechanism for continuous-form stationery advanced from the supply compartment A¹ to the record compartment A²; and C, differential cam 50 mechanism for initially positioning the stationery and assisting the re-folding of the same.

The register is of conventional construction having a bottom wall 6, side walls 7, a platen forming top 8, and a transverse wall 9 for separating the supply compartment from the record

compartment and forming a support for the mechanisms B and C.

The supply compartment A¹ is provided with a forwardly swinging door 10 which is pivoted to the casing at 11, to permit access to the compartment for loading, and is normally held in its closed position by means of a skeleton cover 12 which partially encloses the platen 8 and is pivotally mounted on the upper central portion of the casing. The supply compartment is provided with a guide roll 13 which is journaled in a pair of slots 14.

The record compartment A² is provided with an upwardly movable cover 15 which is pivotally mounted on the casing at 16 and permits access to the record forms which are projected into the compartment by the feed mechanism. The upper front portion of the casing is provided with a divider plate 17 which serves to separate the record strip of stationery from the original copy which is 20 dispensed by the machine.

The feed mechanism B comprises a crank shaft 18 journaled in the walls of the casing, carrying a pair of lower feed rolls 19 and equipped at its outer end with a hand crank 20; and upper feed 25 rolls 21 mounted on a shaft 22 journaled in a housing 23 provided at the rear end of the skeleton cover 12. The crank shaft 18 is provided with a ratchet wheel 24 which is acted upon by a pawl (not shown) to prevent rearward rotation 30 of the shaft. The outer wall of the casing is provided with a leaf spring 25 adapted to lock the crank 20 when it is rotated to the position against the spring pressed plunger 26. Thus it will be understood, to operate the machine the plunger 35 26 is depressed and the crank will then be free to make one complete revolution whereupon it will again be locked by the spring 25.

The aligning and re-folding mechanism C has a pair of register pins 27 which are slidably 40 mounted in holes provided in the lower feed rolls 19. The side walls of the wheels are provided with slots 28 which are impaled by pins 29 projecting laterally from the pin shanks to permit limited movement of the pins in the sockets. The pins are urged outwardly by compression springs 30. A pair of fixed cams 31 are mounted on the transverse wall 9 by means of cap screws 32 and project rearwardly into the path of the pins 29 so that the pins will 50 automatically be retracted from engagement with the stationery during a portion of each revolution of the crank shaft 18. The latter cams insure the retraction of the pins from the stationery when they reach the position shown in 55

Fig. 4. This happens during every revolution of the lower feed rolls. In order to retract the pins at the beginning of each alternate revolution of the feed roll a jack shaft 33 is provided 5 and has an actuating arm 34. The shaft is further provided with a pair of arms 35 which may be swung downwardly into the path of the pins 29 to retract the register pins 27. The crank shaft 18 is provided with a gear 36 which 10 is in mesh with a cam gear 37 journaled on a forward extension of the wall 9 by means of a cap screw 38. The gear 37 has twice as many teeth as the gear 36 so that it makes but one revolution for each two revolutions of the crank shaft. The cam gear has a cam lug 39 which 15 serves to operate the arm 34 to retract the register pins. As shown in Fig. 5, the jack shaft is provided with a torsion spring 40 which urges the arms 35 upwardly and the arm 34 into engagement with the cam lug 39.

When the crank 20 is in its normal locked position shown in Figs. 1 and 5, the register pins 27 extend upwardly above the platen 8 and facilitate initial positioning of the continuous-form stationery 41 which is led from the compartment A' over the platen into the bight of the feed mechanism. The upper strip 42 is directed above the divider plate 17 while the record strip 43 extends beneath said plate. The skeleton 30 cover 12 may then be closed to the position shown in Fig. 1 and the device is ready for operation. After a set of forms have been filled in the plunger 26 is compressed and the crank 20 given one revolution to turn out one form length. As 35 shown in Figs. 2, 3 and 4, the lower feed rolls have a flattened or cut away portion 44 so that the pressure between the rolls is momentarily released while the perforations in the stationery are engaged by the pins 27. This enables the 40 pins to perform part of the feeding operation while free from the rolls and permit the forms to be brought into perfect register. After the rotation the original form 42 may be severed by drawing upwardly against the tear-off edge 45 provided at the rear end of the skeleton cover 12. 45 Assuming that the cam gear was so positioned during the first revolution of the crank that it did not operate to retract the pins, the pins will carry the record strip forwardly to the position shown in Fig. 4 where they will be retracted 50 from the stationery by means of the fixed cams 31. On the next revolution the cam gear will cause the arms 35 to retract the pins at the beginning of the feeding stroke and this will permit the next record form to be projected rearwardly in the compartment A' as shown in Fig. 3. 55

The foregoing detailed description has been given for clearness of understanding only, and no unnecessary limitations should be understood therefrom, but the appended claims should be construed as broadly as permissible, in view of the prior art.

What I claim as new, and desire to secure by Letters Patent, is:

1. In an autographic register casing having a supply compartment, a platen and a record compartment; feed rolls adapted to advance continuous-form stationery strips from said supply compartment over the platen to the record compartment; retractable register pins moving in timed relation with respect to said feed rolls and adapted to engage and register in turn each form length of said strips; and vertically movable

means mounted on said casing, adjacent to said feed rolls, driven in timed relation to the feed rolls, for retracting the pins from the stationery during the advancement of each alternate form-length. 5

2. A device as specified in claim 1, in which two lower feed rolls are provided, the register pins are movably mounted on said feed rolls, and said feed rolls have cut-away portions for releasing the strips momentarily while the perforations are engaged by the pins. 10

3. In an autographic register casing having a supply compartment, a platen, and a record compartment; feed rolls adapted to draw one form length of continuous form stationery strips provided with register perforations over said platen during each revolution; retractable register pins mounted on said feed rolls to engage and register in turn each form length of said strips; oscillatable means mounted on said casing for disengaging the stationery from the pins; and differential-cam means driven in timed relation to the movement of the feed rolls for actuating said oscillatable means during each alternate revolution of the feed rolls. 20

4. A device as specified in claim 3, in which the register pins are yieldingly urged outwardly to engage the stationery, and fixed cam-means are provided to hold the pins retracted during a portion of each cycle. 25

5. In an autographic register having a casing provided with a platen and a record compartment; feed means adapted to draw one form-length of continuous-form stationery strips provided with register perforations over said platen 35 during each operation; alining and refolding means driven in timed relation to said feed means adapted initially to engage the perforations to register the forms over the platen and to project a record strip of forms into the record compartment; and oscillating means mounted on said casing adjacent to the feed means and driven in timed relation thereto for disengaging the refolding means from the record strip during each alternate operation of the feed means. 40

6. In an autographic register having a casing provided with a supply compartment, a platen and a record compartment; an upper feed roll and a lower feed roll journaled in said casing and adapted to cooperate and advance continuous-form stationery provided with register perforations over said platen to the record compartment; yieldingly urged register pins mounted in said lower feed roll to engage said perforations; fixed-cam means for holding the pins retracted during a portion of each revolution of the lower feed roll; vertically movable cam-means mounted on said casing for retracting said pins during another portion of each alternate revolution of said lower feed roll; and a driving shaft for actuating said feed rolls and cam-means in timed relation. 55

7. A device as specified in claim 6 in which the movable cam-means comprises a jack shaft journaled in said casing and provided with pin 65 retracting arms and an actuating arm, and a cam gear for operating said actuating arm, said cam gear being in mesh with a gear on the driving shaft and having twice as many teeth as the latter so as to make one revolution for each two revolutions of the lower feed roll. 70

LOUIS JENSEN.
